BLOWER FOR HEAT TREATING FURNACE

Theodore W. Munford, Ottawa Hills, Ohio, assignor to Surface Combustion Corporation, Toledo, Ohio, a corporation of New York

Application October 9, 1939, Serial No. 298,538

3 Claims. (Cl. 308—77)

The present invention relates to a blower for stirring up or circulating the atmosphere in a furnace chamber wherein articles are being annealed or otherwise heat treated. In blowers of this type the fan shaft bearing nearest the fan tends to become overheated due to the conduction of heat along that portion of the fan shaft which projects into the furnace chamber. It is therefore the object of the present invention to provide a blower of such construction that the tendency of the fan shaft bearing to overheat shall be reduced to a minimum.

In the accompanying drawing wherein the preferred form of the invention is shown—

Fig. 1 is a vertical section through the improved blower, a portion of the furnace base being also shown in outline;

Fig. 2 illustrates on a somewhat larger scale a feature shown in Fig. 1, and

Fig. 3 is a more or less diagrammatic representation of the type of furnace with which the invention has special utility.

The furnace illustrated in Fig. 3 comprises a base 10, a removable heating hood 11, an inner cover 12 and a stool 13 on which the work to be heat treated is supported. The blower fan is indicated at 14, it being noted that the fan shaft, generally indicated at 15, extends through the furnace base.

Referring now more particularly to Fig. 1, there is provided in the furnace base an upright sleeve 16 through which the fan shaft 15 extends into the furnace chamber, the shaft being provided with a driving pulley 19 at its lower end. However, it will be understood that the shaft may be otherwise driven. The upper bearing for the shaft is indicated at 20 and the lower bearing at 21. The supporting means for the bearings comprises a lower member 22 surmounted by a cap 23 adapted to be secured to the underside of the furnace base 10 as by bolts 24 extending through the rim of the cap. The cap has a depending circular wall 25 provided with a bottom flange to which the member 22 is detachably secured.

It is preferred that the upper portion 17 of the shaft 15 shall not be solid but tubular and that it be made of a material whose heat conductivity is substantially less than that of the lower shaft portion 18. More particularly the upper shaft portion is preferably made of heat resisting alloy and the lower portion of ordinary steel, the two portions being welded together at their abutting ends. The lower shaft portion may project a short distance into the upper portion as indicated at 18' but in such case, in order to reduce the

rate of heat transfer from the tube to the inserted portion, it is preferred that the contact be discontinuous such as if afforded, for example, by squaring the inserted portion. The lower end of the shaft portion 17 is surrounded by a heat absorbing seal comprising a series of circumferential grooves and ridges 26 formed in the upper part of a hub 27 which houses the bearing 20. It will be understood that heat at the lower end of the shaft portion 17 is absorbed and conducted away by the ridges 26. Lubricant is supplied to the bearing 20 by a pressure grease tube 28.

Secured to the shaft section 18 for rotation therewith is the impeller or runner 30 of a centrifugal pump comprising a circular casing 31 having a central bottom inlet 32 for cooling medium, the casing being supported by a sleeve 33 which is detachably secured to the underside of the hub 27. A packing 34 within the sleeve prevents cooling fluid from flowing into said hub. Extending upwardly from the pump casing is a circumferential row of fluid discharge tubes 35 whose upper ends are bent toward the hub 27 to discharge thereagainst.

Carried by and preferably integral with the structure 22 is a container 36 adapted to hold a supply of cooling liquid, the cooling liquid level being above the inlet 32, it being noted that the side walls 38 of the container extend upwardly into engagement with the depending wall 25 of the cap 23 to form a closed space above the container. The hub 27 of the cap preferably carries a trough 39 which receives cooling liquid discharged from the tubes 35, it being understood that when the trough is full the liquid overflows and drops back into the container 36. The primary purpose of the trough is to afford a substantial degree of protection to the bearing 20 in case the rotation of the fan shaft is temporarily stopped while the furnace is hot. Inasmuch as the outside face of the container 36 is exposed to the surrounding atmosphere, the liquid in the container will ordinarily be maintained sufficiently cool to obviate the necessity of special cooling as by flowing fresh cooling liquid into the container.

Moreover, depending from the pump casing 31 is a circular baffle or skirt 38' spaced inwardly from the adjacent side walls 38 of the container for insuring that liquid above the pump shall flow downwardly along the relatively cool side walls 38 to a point adjacent the bottom of the container before flowing to the pump inlet 32. Webs or fins 29 on the outside walls of the container also assist in dissipating heat from the container walls

and also serve to add strength to the structure 22, it being noted that said webs extend vertically.

A closed cooling system of the kind described has special utility in steel mills because of the minimum attention required and because instead of using regular mill water which is likely to be dirty the container 36 may be filled with clean water with or without a non-freeze solution as conditions may require.

40 indicates a breather pipe in the space above the normal liquid level in container 36 and 41 a sight glass for observing the level of the liquid. The cooling liquid may be replenished by removing a plug 42 at the upper sight glass connection.

From the foregoing description it will be seen that the present invention provides a cooling system which is relatively simple and well adapted for its intended purpose.

What I claim is:

1. In combination, a support adapted to be secured to the underside of a furnace chamber and having a hub depending therefrom, walls depending from said support to form a container for cooling liquid, a shaft extending upwardly through the bottom of the container and through and beyond said hub for projection into said chamber and having at its upper end a fan for stirring up gases in said chamber, a shaft bearing housed by said hub, and means housed by said walls for drawing cooling liquid from said container and for delivering the same about said hub for cooling the latter, whereby to cool said bearing, said means comprising a hollow body having an inlet facing the bottom of said container, a skirt depending from said body for causing liquid above said body to flow between the skirt and the adjacent walls of the said container before reaching said inlet, and a rotary member housed by said body and connected to said shaft for rotation therewith for drawing 40 liquid into said body.

2. In apparatus of the class described, the combination of a drive shaft having an extension for insertion into a heated chamber through a bottom wall thereof for driving a device within the chamber, a container adapted to hold a body of cooling liquid, a cover for the container for closing off the same from the surrounding atmosphere, said cover being adapted for securement to said wall outside of said chamber, said shaft extending upwardly into the container and through and beyond said cover to form said extension, a bearing for the shaft, a housing wherein said bearing is positioned, said housing depending from said cover, and means for drawing liquid from 10 the container and for discharging the same about said housing for cooling the latter whereby to maintain said bearing relatively cool.
3. In apparatus of the class described, the combination of a drive shaft having an extension for 15 insertion into a heated chamber through a bottom wall thereof for driving a device within the chamber, a container adapted to hold a body of cooling liquid, a cover for the container for closing off the same from the surrounding atmosphere, said 20 cover being adapted for securement to said wall outside of said chamber, said shaft extending upwardly into the container and through and beyond said cover to form said extension, a bearing for the shaft, a housing wherein said bearing is positioned, said housing depending from 25 said cover, a pump for drawing liquid from said container and comprising a rotary element secured to said shaft and a casing for said element, means depending from said housing for supporting said casing, and means carried by said casing for discharging liquid from the latter about said 30 housing for cooling the latter whereby to maintain said bearing relatively cool.

THEODORE W. MUNFORD.
